UNITED STATES PATENT OFFICE.

PHILIP HANO, OF NEW YORK, N. Y.

AUTOGRAPHIC REGISTER.

No. 831,949.

Specification of Letters Patent.

Patented Sept. 25, 1906.

Application filed December 20, 1905. Serial No. 292,675.

To all whom it may concern:

Be it known that I, PHILIP HANO, a citizen of the United States, residing at New York city, county and State of New York, have invented new and useful Improvements in Autographic Registers, of which the following is a specification.

By means of this invention the operation of an autographic register is facilitated or expedited. The arrangement is such that both hands of the operator or salesman can be utilized without interfering with one another, and as a record is made or duplicated or multiplied the strip or the paper written on or utilized can be rapidly fed along to allow subsequent records to be made at rapid intervals. By providing a slip or friction storage or roller for a strip or record coming from the register such record can be tightly or compactly wound, but without danger of the paper or record being torn or injured. The device is also shown with means for keeping the strips of paper flat or preventing shifting and with other features, as presently explained.

This invention is set forth in the following specification and claims and illustrated in the annexed drawings, in which—

Figure 1 is a plan view of an autographic register embodying this invention. Fig. 2 is a sectional side elevation of Fig. 1. Fig. 3 is a section along x x , Fig. 1. Fig. 4 is a view like Fig. 1, showing the slide extended. Fig. 5 is a side elevation of Fig. 4. Fig. 6 is an inverted plan view along y y , Fig. 2. Fig. 7 is section along z z , showing a storage or winding roller for a record sheet or strip. Fig. 8 shows a jaw. Fig. 9 is a sectional detail.

In the drawings is shown a frame or support a , which can be composed of two hinged sections or of any other suitable construction.

In the drawings is shown a hinge at b .

A writing-table is shown at c and a top plate at d . The top plate has an opening, as usual, to expose the paper or record strip or strips e at the table c , so that writing can be done on the strip. Three record-strips are shown in the drawings; but of course another number of strips could be inserted into the machine.

Carbon or transfer paper is shown at f . Such transfer-sheets are of course applied in such number as required or to correspond to the number of transfer-copies required.

A carriage or slide is shown composed of a

frame-like structure or side bars g and cross or front piece h . Fixed above the front bar h is a bridge piece or strip i , between which and the cross-piece h the record-sheets or some of them can be extended. This strip or metal bar i forms a jaw or a member of a clamp, the other member of which is shown at k . The jaw member k is movable or can swing about a fulcrum or pivot o and is provided with an arm m , jointed or pivoted at p to a rod or link q . The leading edges or front part of the record-strips are extended between the jaws i k , and when the carriage moves forward the strips are gripped or the movable jaw k closed against the fixed jaw i , and the record-strips are drawn forward a certain extent. On the return of the carriage the jaws open or the movable jaw moves away from the fixed one, and the carriage on its return leaves the sheets undisturbed or with the front portion drawn out, as described. The drawn-out portion of the sheets or of some of them could be ripped or torn off at an edge of bar or jaw i , which is sharpened or formed as a ripper. One or more of the sheets could also be stored in the machine or register, if desired. The slide is connected by link r to a lever s , fulcrumed at t and having one arm provided with a handle u . As the lever is moved back and forth it reciprocates the carriage. The lever, or rather the link r , is connected to the rod q , so that as the link moves forward the rod q closes the jaw k to jaw i to clamp the paper and then propel the carriage. The return movement of the rod q pulls on arm m to open jaw k and then return the carriage. The record-strips e are shown in form of rolls which can be unwound from spindles 2 . The transfer or carbon sheets extend from box or holder 3 , whose cover 4 can be held closed by the superposed removable top plate d .

At a suitable point or pivot 7 on the slide or piece h is a ratchet-rack 8 , engaging a ratchet-wheel 10 on a spindle 11 . A wind-up sleeve 9 is frictionally mounted on the spindle 11 —that is, a spring 14 is interposed between the spindle and sleeve 9 . One of the record-strips can be led about a roller 12 on the slide to the storage-roller 9 and wound up. The slip connection or friction-spring 14 prevents the stored strip being wound too tight or being torn, since in case the stored strip is stretched tight the spindle can slip or rotate idly in the sleeve. The ratchet-rack of course clicks idly over ratchet-wheel 10 .

when running in one direction, but engages the ratchet-wheel to wind the strip when running in the opposite direction.

Under the table *c* is shown a guide or channel 15 and at its front a lip or stop 16. The slide or carriage is shown with rods 17, carrying a cross-brace 18, in which plays the driving-rod *q*, linked to lever *s* and actuating the slide or carriage. A slight longitudinal play of rod *q* is sufficient for this rod to operate the jaw *k*, and after such jaw has been opened or closed the rod *q* will move the carriage in required direction. The cross-brace 18 can be set by nuts 19 so as to strike stop 16 sooner or later and adjust the travel or throw of the carriage to the required length or stretch of paper required from the strip for each registration. The rod *q* is shown with a guide-piece 20 screwed or attached thereto, which 20 piece runs in track 15. The rod *q* thus runs steadily or easily. A tension is shown for the various rolls or spindles 2. A screw 21 can be set to press a spring 22 more or less against the end of its respective roll or strip, as required. The spring 22 can easily be formed from flat plates screwed at one end to the frame or base, while the free end is free to be set by its set-screw. The antishift-spring 23 serves to keep the paper flat and prevents 30 the same from shifting or creeping. This spring can be formed of a flat plate secured at one or both ends to the top plate, or rather its under face, and by suitably turning screw 24 a part of this spring can be suitably pressed 35 to the paper to flatten and prevent shift of the same. The rack 8 is shown held up by box 25, which also serves as a guide for the rack as it moves back and forth. The spindle 11 is held in place by a lock or bolt 26, and 40 when this bolt is freed or slid out of the notched part of the spindle the latter can be withdrawn, and the sleeve 9 will then be freed, and its spring 14 can be withdrawn. The parts can be assembled by replacing the 45 spring, running the spindle through its bearings in the frame and through the sleeve, and locking the slide or bolt 26.

The machine is adapted to use printed forms and to keep the same in alinement,

these printed forms being on endless strips wound on rolls. The single movement of the hand for moving lever *s* in either direction will grip or release the paper at the same time as moving the carriage one way or another. The rods 17 form a rest when the carriage is extended to prevent the paper or record strips from curling or sagging. The top plate *d* can be connected in a variety of ways, a hinge 27 being shown in the example illustrated.

What I claim as my invention, and desire to secure by Letters Patent, is—

1. An autographic register comprising a paper-supply and writing-table, a slide having paper-gripping jaws for moving the paper, an actuating-rod for the jaws, a guide for the slide provided with a stop, and a cross-brace adjustable along the slide and made to loosely support the jaw-actuating rod and coact with the stop. 70

2. An autographic register comprising a paper-supply and writing-table, a slide with gripper for moving the paper, a gripper-actuating rod and lever made to reciprocate the slide, a track or guide with a stop under the 75 table, a guide-piece on the gripper-actuating rod engaging the guide, rods moving with the slide and a cross-brace adjustable along the rods and made to coact with the stop.

3. An autographic register comprising 80 paper-supply rolls, a writing-table, a slide for moving the paper, an antishift-spring extended across the paper and the table, and a screw for pressing said spring to the paper.

4. An autographic register comprising 85 paper-supply rolls, a writing-table, a top plate, means for moving the paper, a spring carried by the top plate and adapted to press onto the paper on the table, and means for adjusting the action of said spring. 90

In testimony whereof I have hereunto set my hand in the presence of two subscribing witnesses.

PHILIP HANO.
